Primary Examiner — Elizabeth A. Albert(74) *Attorney, Agent, or Firm* — Merchant & Gould P.C.(57) **CLAIM**

The ornamental design for a bottle opener, as shown and described.

DESCRIPTION

FIG. 1 is a perspective view of a bottle opener showing a new design;

FIG. 2 is a top view of the bottle opener of FIG. 1;

FIG. 3 is a bottom view of the bottle opener of FIG. 1;

FIG. 4 is a front view of the bottle opener of FIG. 1;

FIG. 5 is a rear view of the bottle opener of FIG. 1;

FIG. 6 is a side view of the bottle opener of FIG. 1.

The broken lines depict unclaimed subject matter and form no part of the claimed design.
